POSITIVE DRIVE SLOW MOTION SPRINKLER

Filed Dec. 24, 1934

UNITED STATES PATENT OFFICE

2,051,287

POSITIVE DRIVE SLOW MOTION
SPRINKLER

William A. Buckner, Fresno, Calif.

Application December 24, 1934, Serial No. 759,079

1 Claim. (Cl. 299—67)

This invention relates to water sprinklers and is directed particularly to slow motion rotary water sprinklers.

In this type of rotary sprinklers, the sprinkler heads—rotating due to the reactionary force of the water flowing from the nozzles—are often subject to sticking, and become inoperative, especially when the water pressure is low and wear has developed with long use. It therefore is necessary to provide an auxiliary drive mechanism in order to assure rotation of the sprinkler head at all times. This problem has heretofore been dealt with by various mechanisms such as those disclosed in my United States Patents Nos. 1,815,395, 1,815,880, and 1,970,126.

The principal object of my present invention is to provide a slow motion rotary sprinkler having a simplified water actuated and pressure responsive mechanism which will intermittently and positively impart rotation to the sprinkler head.

It is also my object to provide means whereby the speed of the positive drive mechanism may be selectively controlled, thereby controlling the number of positive impulses imparted to the sprinkler head.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

In the drawing similar characters of reference indicate corresponding parts in the several views:

Figure 1 is an elevation, partly in section, of my improved sprinkler.

Figure 2 is a top plan view partly in section taken on line 2—2 of Figure 1.

Figure 3 is a bottom plan view of the water distributing disc.

Referring now more particularly to the characters of reference on the drawing, the numeral 1 denotes a cylindrical housing formed with a tapped bottom passage 2 adapted to be secured to a water supply pipe. In watertight engagement with the housing 1 is a cap 3 formed with an upstanding bearing sleeve 4. Rotatable in the bearing sleeve 4 is the tubular spindle 5 formed on its inner end with a flange 6. A thrust collar 7 is disposed on the sleeve 5 between the flange 6 and a recessed bearing shoulder in the cap 3. The thrust collar 7 also compresses against a packing gasket 8 in its recess

in the sleeve 4, which prevents water leakage between the spindle 5 and the bearing sleeve 4. The usual grease cup 9 affords lubrication to the bearing surface of the sleeve 4.

Threaded on the upper end of the spindle is 5 the rotatable sprinkler head H having outwardly and upwardly projecting sprinkler arms 10 which terminate in nozzle members 11. One nozzle member is cut through or slotted as at 12 in order to form a reactionary spray nozzle adapted 10 to cause rotation of the sprinkler head.

Extending radially from the flange 6 is an arm 13 formed with a downwardly depending finger 14 adjacent the inner periphery of the housing 1 and corresponding on the outer side to the 15 curvature of the side wall. The trailing edge of the finger 14 is formed at an angle as at 15 while the remainder of the finger on the inner side tapers toward the leading edge as shown.

Threaded into the bottom of the housing 1 directly over the incoming water passage and depending into a chamber 16 is a water distributing disc 17 having a central orifice 18 and a plurality of tangential passages 19 cut about its rim on a vertical diagonal. The disc 17 is provided on its 25 lower face with downwardly tapering nubs 20 which surround the central orifice as well as engage the housing at the bottom of the chamber 16 to form a strainer for the water entering the chamber 16 from the passage 2. 30

On the upper face of the water distributing disc 35 is an upstanding bearing and water passage 21 concentric with the central orifice 18 and of less diameter than the disc. Adapted for selective threaded engagement in the central orifice 18 is a 35 flow reducing core 18a having an orifice of reduced diameter therein.

A substantially rectangular driving member 22 having a bearing slot 23 formed therein and adapted for cooperative engagement with the 40 bearing 21 rests on the upper face of the water distributing disc 17 and is both rotatable and transversely movable on the bearing. The driving member 22 has a contact head 24 on one end thereof, the outer end of the head being, when in 45 normal operative position, immediately adjacent as well as conforming to the curvature of the housing. The contact head 24 has an angular face 25 on its leading edge, the angle of the face corresponding to the angle of the face 15 on the 50 finger 14.

Spaced about the sides and inner end of the driving member and extending out therefrom are vanes 26 and 26a respectively, which are in the path of the streams of water thrown out of the 55

tangential passages 19, so as to be engaged by such streams, and thus impart rotation to the member.

In operation, water under pressure flows from the source of supply into the sprinkler housing, part of the flow passing through the central orifice 18 and out through the bearing sleeve 21, while the remainder flows between the strainer nubs into the chamber 16 from whence it flows 5 through the tangential passages 19 and strikes the vanes 16 and 16a on the driving member 22. This causes the driving member to rotate and to 10 also be thrown centrifugally to its limit of outward movement, or to position relative to the bearing 21 as is shown in Figure 2 in full lines. Then, as the driving member 22 rotates, the face 15 of the contact head 24 strikes the face 15 of the finger 14 which results in the finger and consequently the sprinkler head being rotated a short 15 distance. The force of the blow when the angular faces come into contact then causes the driving member to move inwardly, or so that it assumes the position indicated in dotted lines in Figure 2. This allows the contact head to slide 20 past the finger and again assume a normal rotative position with the pressure of water against the vanes.

The above described function prevents the rotatable sprinkler head from sticking and becoming 25 inoperative because if at any time the reactionary force of the flow from the split nozzle 12 is not sufficient to rotate the sprinkler head, the intermittent contact of the contact head and the finger will drive the sprinkler head around a certain distance and also prevent any tendency 30 for the parts to stick.

The speed with which the driving member rotates within the housing may be controlled by the 35 selective insertion of a core 16 having a larger or smaller orifice. The greater the volume of water

that is forced through the passages 19, the greater the speed of the driving member.

The tapered nubs 20 serve as a strainer and substantially all foreign matter in the water is prevented from flowing into the chamber 16 with 5 possible jamming of the driving member as it flows out of the passages 19. All such foreign matter will be forced through the central orifice 18.

From the foregoing description it will be readily seen that I have produced such a device as substantially fulfills the objects of the invention as set forth herein.

While this specification sets forth in detail the present and preferred construction of the device, 15 still in practice such deviations from such detail may be resorted to as do not form a departure from the spirit of the invention, as defined by the appended claim.

Having thus described my invention, what I 20 claim as new and useful and desire to secure by Letters Patent is:

A sprinkler comprising a housing, a sprinkler head having a vertical passage spindle projecting into and turnably mounted in the top of the housing, a water intake passage member formed with the housing and depending therefrom, a tubular element projecting upwardly into the housing from the bottom thereof in axial alignment with the spindle and communicating with the intake 25 passage, there being openings outwardly of said element and also providing communication between the housing and intake passage, means actuated by water flowing under pressure through said openings to intermittently rotate the spindle, 30 and a removable flow restricting plug mounted in said tubular element whereby said plug may be interchanged with one having a different sized flow restricting passage so as to alter the pressure of the water flowing through said openings. 35
